CLAIM

The ornamental design for a device holder, as shown and described.

DESCRIPTION

FIG. 1 is a front perspective view of a device holder; FIG. 2 is a front view of the device holder of FIG. 1; FIG. 3 is a rear view of the device holder of FIG. 1; FIG. 4 is a right side view of the device holder of FIG. 1; FIG. 5 is a left side view of the device holder of FIG. 1; FIG. 6 is a top view of the device holder of FIG. 1; and, FIG. 7 is a bottom view of the device holder of FIG. 1. The broken away symbols in the drawings indicate that any portion of the article beyond what is shown forms no part of the claimed design.
